UNITED STATES PATENT OFFICE.

JOHN KYLE, OF PHILADELPHIA, PENNSYLVANIA.

PRINTER'S BEARER STRIP.

Application filed July 16, 1925. Serial No. 43,961.

To all whom it may concern:

Be it known that I, JOHN KYLE, a citizen of the United States, residing at Philadelphia, county of Philadelphia, and State of Pennsylvania, have invented a new and useful Printer's Bearer Strip, of which the following is a specification.

My invention relates to a new and useful bearer strip for printing presses, which is adapted to impart a constant and uniform surface speed to the inking rolls of the press as they pass over the form or plate, regardless of the amount of type or printing area in said plate or form.

15 In printing from forms or plates, in which the area covered by the type or printing surface is relatively small and scattered over the entire form or plate and particularly in printing individual lines, such as rulings or 20 the like, there has been considerable difficulty in inking the form, because the inking rolls received their rotary motion from contact with the printing areas. Thus, if there was a blank space between several detached 25 printing areas, then the printing roll would cease to rotate until it was again engaged by the next succeeding printing area. When thus engaged suddenly, the rolls will scrape off considerable ink on to the edges of printing 30 surface or type, before such printing surface sufficiently engages the rolls to 35 revolve them again.

Furthermore, in printing individual lines, and particularly lines extending longitudinally of the direction of travel of the inking rolls over the plate, such lines of printing surfaces soon wear a groove into the relatively soft and plastic surface of the inking rolls, if such printing areas are depended 40 upon, to revolve the rolls.

Various attempts have been made to overcome these difficulties in printing, that is, in the inking of detached or narrow lines of printing surfaces. One of the means resorted to has been a strip of wood or metal, commonly known as bearer strip, of the same level or height as the printing surface, clamped or strapped in with the plate or form, or clamped alongside thereof, which 45 strip, extending longitudinally of the direction of travel of the rolls would engage and revolve the same. This method, however, has not been entirely satisfactory because within a relatively short time the bearer strip wears a groove into the relatively soft and plastic surface of the inking rolls by

traveling over the same area and thereby would become ineffective, that is, would not continue to revolve the rolls.

Attempts have also been made to provide 60 suitable annular friction surface of a rigid material such as metal, alongside the rolls and on the same shafts or spindles, of the diameter as the inking rolls, which annular friction surface would be frictionally engaged by a hard and rigid straight surface thereby revolving the rolls. This method, however, has also been found to be ineffective, because the diameter of the rolls decreases gradually after constant use, due to 65 the gradual drying out of the roll material, and the attendant shrinkage of the rolls. Due to the different diameters thus obtained between the rolls and the annular friction surface, it was found that the surface speed 70 of the rolls would not equal the actual speed with which they travel over the form, thereby also causing a slight scraping off of the ink, on to the edges of the type, which, as will readily be seen, will prevent a clear impression or print from the plate.

In order to overcome these difficulties I have devised a bearer strip having a relatively wide body of a lesser height than the printing surface, and adapted to be clamped 85 in the frame alongside of the plate or form, to extend longitudinally of the direction of travel of the ink rolls, and having thereon a relatively narrow strip of the same level as the printing surface and disposed at an angle to the body, and hence at an angle to the direction of travel of the rolls.

By my novel construction, the ink rolls will be engaged by the narrow surface of the bearer block in constantly varying positions, 90 and thus no groove will be worn into the surface of the rolls. Furthermore, since the rolls do not ride onto the form and the bearer strip in the same position any two times, the bearer surface of the bearer block 100 will also engage a different initial position upon the rolls.

For the purpose of illustrating my invention, I have shown in the accompanying drawings forms thereof which are at 105 present preferred by me, since they will give in practice satisfactory and reliable results, although it is to be understood that the various instrumentalities of which my invention consists can be variously arranged and 110 organized and that my invention is not limited to the precise arrangement and

organization of these instrumentalities as herein shown and described.

Referring to the drawings:—

Figure 1 represents a plan view of a plate or form set up with two bearer blocks embodying my invention.

Figure 2 represents an end elevation of the same.

Figure 3 represents a perspective view of 10 a bearer block embodying my invention.

Referring to the drawings, in which like reference characters indicate like parts, 1 designates the metallic frame commonly employed on printing presses, in which the 15 form is made up, of suitable type or plates 2, by the means of the clamps 3. One or several bearer blocks 4 of my novel construction may be clamped inside the frame in a manner shown in Figure 1, disposed 20 longitudinally of the direction of travel of the ink roll 5. The bearer block 4 is provided with parallel edges 6, whereby the same is clamped, and an upper surface 7 which is below the printing surface. The 25 bearer strip 8, protruding from the upper surface 7 of the block, is formed integrally therewith, and is disposed at an angle to the body of the bearer block. The upper surface of the strip is substantially on the level 30 of the printing surface.

In setting up a form one or several of these bearer blocks may be clamped in the frame and the height of the bearer surface 8 may then be adjusted by backing it up, 35 if necessary, with thin sheets of paper, as is well known in the art.

It will now be apparent that I have devised a novel and useful printer's bearer strip which embodies the features of advantage enumerated as desirable in the statement of the invention and the above description, and while I have, in the present instance, shown and described a preferred embodiment thereof which will give in

practice satisfactory and reliable results, it 45 is to be understood that such embodiment is susceptible of modification in various particulars without departing from the spirit or scope of the invention or sacrificing any of its advantages.

Having thus described my invention, what I claim as new and desire to secure by Letters Patent is:—

1. A printer's bearer strip of the character stated, comprising an elongated body portion having substantially parallel longitudinal sides and an upper surface of a lesser height than the height of the printing surface, and an elongated bearer strip on said upper surface, disposed at an angle to said 50 parallel sides.

2. A printer's bearer strip of the character described, comprising an elongated body portion having substantially parallel longitudinal sides and an upper surface of lesser height than the height of the printing surface, and a bearer strip on said upper surface, formed integral with said body portion, and disposed at an angle to said 55 parallel sides.

3. A printer's bearer strip of the character stated, comprising an elongated body portion having substantially parallel longitudinal sides and of a height less than the height of the printing surface and an upper elongated bearer strip carried by said body portion, disposed at an angle to said 60 parallel sides.

4. A printer's bearer strip of the character stated, comprising an elongated body portion having substantially parallel longitudinal sides and of a height less than the height of the printing surface and an upper elongated bearer strip carried by said body portion, and formed integral therewith, disposed at an angle to said 65 parallel sides.

JOHN KYLE.
